UNITED STATES PATENT OFFICE

128,607

DESIGN FOR A GAME BOARD

Samuel J. Tatem, Collingswood, N. J.

Application May 1, 1941, Serial No. 100,735

Term of patent 7 years

To all whom it may concern:

Be it known that I, Samuel J. Tatem, a citizen of the United States, residing at Collingswood, in the county of Camden and State of New Jersey, have invented a new, original, and ornamental Design for Game Boards, of which the following is a specification, reference being had to the accompanying drawing, forming part thereof.

Figure 1 is a view in top plan of a game board embodying my new design.

Figure 2 is a view in end elevation of the board.

Portions of the design are lined for contrasting colors.

I claim:

The ornamental design for a game board, as shown and described.

SAMUEL J. TATEM.
